EX

OF D 16, 924

UNITED STATES PATENT OFFICE.

PETER T. GRAVES, OF MILWAUKEE, WISCONSIN, ASSIGNOR TO THE MILWAUKEE CHAIR COMPANY, OF SAME PLACE.

DESIGN FOR A CHAIR-BACK.

UNITED STATES PATENT OFFICE.

PETER T. GRAVES, OF MILWAUKEE, WISCONSIN, ASSIGNOR TO THE MILWAUKEE CHAIR COMPANY, OF SAME PLACE.

DESIGN FOR A CHAIR-BACK.

SPECIFICATION forming part of Design No. 16,924, dated October 5, 1886.

Application filed August 31, 1885. Serial No. 175,849. Term of patent 7 years.

To all whom it may concern:

Be it known that I, PETER T. GRAVES, of Milwaukee, in the county of Milwaukee and State of Wisconsin, have invented and produced a new and original Design for Chairs, of which the following is a specification, reference being had to the accompanying photograph, and to the letters or figures of reference marked thereon, which form a part of this specification.

The accompanying photograph is a perspective view of a chair of my new ornamental design. This chair is, in its general form and configuration, such as is commonly known as a "dining-room" chair, having a seat and four legs, one at each of its four corners, and a back of two upwardly-extending posts, and cross-bars from one post to the other. In the chair there are three rounds, *a a a*, cut or turned in spiral grooves to represent twisted ropes. One of these rounds is in front, extending from one front leg to the other, and the two remaining rounds are located one on each side of the chair, extending from one post to the other. At the top is a cross-bar, *b*, which is also made with spiral grooves to represent the twisted rope in form. These spiral-

shaped rounds and the spiral-shaped cross-bar are straight rods, and the cross-rod in the back is placed above the other plain cross-bar. Below the cross-bar *b*, and at a distance therefrom, and at a distance from each other, are two other cross-bars, each attached to and extending from one of the upright posts of the chair-back to the other post, and the space between the two posts of the back and the two lower cross-bars is covered or occupied by cane lattice-work attached at its edges to the posts and cross-bars.

What I claim as new, and desire to secure by Letters Patent, is—

The design for the back of a chair, composed of two upright side posts, two cross-bars extending from post to post, the included space being occupied by lattice-work, and the independent straight top cross-bar, *b*, extending from post to post and having a curved spiral surface, as shown and described.

In testimony whereof I affix my signature in presence of two witnesses.

PETER T. GRAVES.

Witnesses:

C. T. BENEDICT,
M. J. SCHINNER.
